(57) **CLAIM**

I claim the ornamental design for a removable shoe lace replacement overlay, as shown and described.

DESCRIPTION

FIG. 1 is a top perspective view of the removable shoe lace replacement overlay with the broken line arrows showing the order of attachment to a shoe;

FIG. 2 is a top view thereof as if it would appear attached to the shoe;

FIG. 3 is another top view with the environmental structure of the shoe removed; and,

FIG. 4 is a bottom view thereof.

In FIGS. 1 and 2, the broken lines show environmental structure in the form of a shoe to which the claimed design is attached. The broken lines and the structure they depict form no part of the claimed design. The broken line arrows in FIG. 1 show the order of assembly and also form no part of the claimed design. The broken lines in FIG. 4 show the boundaries of the claim and form no part of the claimed design.
